CONTAINER SUITABLE FOR DROPPING
FROM AIRCRAFT AND THE LIKE

Edward Ralph Campbell, Ivanhoe, Kenneth Moreton Frewin, Elsternwick, Frank Wentworth Lennox, Toorak, and Rowland Price Morris, North Brighton, Victoria, Australia, assignors to Air Supply Packs Proprietary Limited, Melbourne, Victoria, Australia

Application June 14, 1944, Serial No. 540,328.
In Australia June 21, 1943

13 Claims. (Cl. 244—138)

1

This invention relates to improvements in containers suitable for dropping from aircraft and the like, and has been devised primarily to facilitate the dropping of food, ammunition and other supplies to ground troops and other personnel in localities which are otherwise difficult of access, but is not limited thereto.

The dropping of supplies including weapons and ammunition is an important factor in modern warfare particularly island warfare and the containers heretofore used for this purpose have, we believe, been relatively unsatisfactory chiefly for the reason that they did not sufficiently protect their contents from the shock of impact with the ground, though they have also been subject to other disadvantages.

Now, the general object of this invention is to provide an improved container for the purpose described which will better protect the contents upon impact with the ground or water and which provides additional advantages some of which are hereinafter described.

One broad feature of the invention resides in a container comprising a plurality of coaxially arranged units including a deformable percussion member and a storage compartment and means detachably securing said coaxially arranged units together, said percussion member containing at least one air compression compartment. The container may be of any desired cross-sectional shape—e. g. circular or rectangular, and the said air compression compartment is preferably sealed.

Another feature of the invention resides in the provision at the end of the container opposite to the percussion member of a housing for a packed parachute. This parachute housing may have a readily removable cover capable of serving as a pilot parachute for the main parachute.

Still another feature of the invention resides in detachably securing together the tubular units forming the body of the container by means of one or more flexible members extending longitudinally of the container and attached to the upper and lower units thereof. For this purpose a cord is preferably passed backwards and forwards externally of the container, such cord being suitably attached to grummets or the like on the upper and lower units of the device the upper grummets being also connected to the shroud lines of the parachute.

The aforesaid percussion member at the lower end of the container is preferably of conical form and may advantageously be formed of multi-ply paper, cardboard or the like as may also the tubular units forming the body of the container.

2 and aforesaid cap or cover at the upper end thereof.

The said percussion member may be provided intermediate its ends with a weakened annulus to facilitate crumpling thereof and ensure that ultimate failure of this member will occur in such a manner as to afford the best protection to the contents of the container.

Still another feature of the invention resides in the provision in the body of the container of one or more transverse diaphragms which are slidable longitudinally therein in close contact with the wall thereof such diaphragms serving not only as partitions for separating different kinds of articles, but also as pistons which, by compressing the air therebelow, provide an additional shock absorbing action.

The container is preferably water-tight to protect the contents and, when loaded, preferably contains sufficient air space to enable it to float in water.

Other features of the invention will appear from the following more particular description.

In the drawings:

25 Figure 1 is a view in sectional elevation showing the preferred form of container in accordance with the invention.

Figure 2 is a view in sectional elevation showing the outer series of component parts of the container.

30 Figure 3 is a view similar to Figure 2 and shows the inner series of component parts.

Figure 4 is a view in plan of the container.

Figure 5 is a fragmentary sectional view to a 35 larger scale and shows details of construction of the percussion nose.

Figure 6 is a similar view showing details of construction of the parachute bucket.

Figure 7 is a detail cross-sectional view of a 40 shock absorbing pad.

Figure 8 is a view in elevation of the container and shows one method of tying the units of the container together.

Figure 9 is a view in cross-section taken on the 45 line 9—9 of Figure 8, and shows one method of lacing the parachute bucket; the percussion nose being similarly laced.

Figure 10 is a view in elevation of a suspension ring.

50 Figure 11 is a view in section of the upper part of the parachute bucket and shows an alternative cover therefor.

Figures 12 and 13 are views in elevation and vertical section respectively of a suspension band.

Figure 14 is a view partly in section and partly

in elevation and shows a method of assembling the container for transport when empty.

Figures 15 and 16 are fragmentary views in cross section showing alternative methods of lacing the parachute bucket and/or percussion nose; 5 and

Figures 17 and 18 are sectional views showing modifications in the construction of the percussion nose.

Referring now to Figure 1 of the drawings, the completed container comprises a tubular body generally designated 10, provided at its lower end with a percussion nose 11 and at its upper end with a parachute bucket 12.

The body is of composite construction and consists of a plurality of inner and outer tubes each of which is preferably formed of multi-ply paper—that is to say, each tube is formed by winding a continuous strip of paper on a former until the required thickness is produced, the various convolutions being adhesively secured together. For the purpose under consideration each tube requires to be of substantial thickness—e. g. three-sixteenths of an inch. All of the tubes are preferably impregnated as with wax to render them waterproof while additionally the outer surfaces are preferably coated with shellac, paint or other approved material.

In lieu of forming the tubes of multi-ply paper, they may be moulded from paper fibre which may, if desired, be impregnated with a synthetic resin. Likewise other alternative materials may be used.

More particularly the body comprises a main outer tube 13 which slidably encloses two coaxially arranged inner tubes 14 and 15 which, together, are equal in length to the outer tube 13 (see Figures 2 and 3).

When assembled in the container the inner tube 15 projects somewhat from the lower end of the outer tube 13 to form a spigot which is received in the upper end of the percussion nose 11. A distance ring 15' is arranged within the lower end of the tube 15 and its upper end forms a shoulder on which is supported a sealing disc 15² which is secured and sealed in position in any suitable way whereby the contents of the container, which are packed into the space above the disc 15², will be protected should the container be dropped in water. The upper end of the inner tube 14 is disposed below the top of the tube 13, thereby permitting the lower end portion of a further inner tube 16 to project into the upper portion of the body tube 13.

A further outer tube 17 is fitted over the tube 16 whereby its lower end engages the upper end of the tube 13. The tubes 16 and 17 together form an extension piece which is used when it is desired to form a container of greater capacity than the body tube 13. It will likewise be evident that any desired number of additional extension pieces may be employed in the same manner as required for particular circumstances.

Arranged within the upper end of the outer extension tube 17 and resting on the upper end of the inner tube 16 is a distance ring 18 the upper end of which forms a shoulder on which a sealing disc 19 is seated some distance below the top of the tube 17, such disc being formed of waxed chipboard or other approved material and being suitably sealed in position in a watertight manner.

The lower end of the parachute bucket 12 is received neatly within the upper end of the extension tube 17 (or within the main body tube 13 if the extension tube is not used) and its lower

end rests upon the peripheral portion of the sealing disc 19.

The parachute bucket 12 is of composite construction and comprises an impregnated main tube 12' formed of suitable material such as multi-ply paper provided externally at its lower end with an external reinforcing ring 12² which may be of similar material, this ring being suitably secured in position such as by screws or rivets and adhesive material (Figure 6).

Likewise coaxially arranged rings 12³ and 12⁴ are secured within the lower end of the tube 12', the adjacent ends of these inner rings being spaced apart to form a circumferential recess in which the peripheral portion of a transverse strengthening disc 12⁵ is located, such disc also being formed of waxed chipboard or the like and serving to prevent collapse of the bucket when the parachute opens.

A further disc 12⁶ provided at its center with a relatively large hole 12⁷ rests at its periphery on the upper end of the ring 12³ and forms the bottom of a compartment in which a folded parachute 19 is housed. The outer end of this compartment is normally closed by a known type of cover 20 formed of canvas or other suitable flexible material such cover comprising a plurality of flaps the free ends of which overlap at the axis of the container and are detachably connected together by suitable fastening means (not shown).

A cord 21 is attached to the top of the parachute by a breaking link (not shown) and in use its free end is fixed to the aircraft on which the device is carried whereby, when the container is dropped from the aircraft, the cord becomes taut and the parachute is pulled from the parachute bucket at the same time releasing the flaps of the canvas cover 20. The breaking link subsequently breaks in the usual way.

The shroud lines 22 of the parachute are connected to a suspension ring 23 (Figure 10) which is conveniently formed of metal, such ring normally resting on the top of the disc 12⁵ in the parachute bucket, and extending through the central hole in the superposed disc 12⁶ as shown in Figure 1.

The suspension ring 23 is preferably provided with a central cross bar 23' which prevents lateral collapse thereof when it is subjected to the shock of the opening of the parachute and which additionally separates the shroud lines 22 from a cord 24 by which the ring is secured to the parachute bucket such cord being arranged as hereinafter described. The cross bar 23' thus also prevents fouling of the shroud lines with the cord 24.

A plurality of closely spaced pairs of circumferentially arranged holes 12⁸ are formed in the lower part of the parachute bucket 12 and such holes extend through the main tube 12', the outer reinforcing ring 12² and the inner ring 12⁴ as best shown in Figures 8 and 9. The latter figure shows 11 pairs of such holes though a lower odd number—e. g. 7—may be provided in order to reduce the length of cords and the time of lacing. While it is not essential to provide an odd number of pairs of holes, an odd number is advantageous when the cord 24 is laced in the preferred manner shown in Figure 9. Thus one end of the cord is passed through one of the pair of holes at the position designated I, then through the lower half of the suspension ring 23 to and through one of the holes at position II. The cord is then 70 returned through the other hole at position II

leaving an exposed loop 24' and is then passed again through the lower half of the suspension ring and so on, to and through each pair of holes in the order indicated by the roman numerals until an external loop 24' is arranged between the holes forming each pair. Finally the free ends of the cord are tied as shown at 24² inside the parachute bucket it being understood that the cord passes through the lower half of the suspension ring at each traverse of the interior of the bucket.

The percussion nose 11 which also is conveniently formed of multi-ply paper similarly to the other parts of the container, is also of composite construction and comprises an outer tube 11' the upper end of which abuts against the lower end of the body tube 13 and which is correctly positioned by the aforesaid projecting lower end of the inner tube 15. Attached to the lower end of the tube 11' is a conical nosepiece 11² the upper end of which is formed with a short integral cylindrical extension which fits neatly within said outer tube 11'.

The cone may conveniently be formed by successively placing single ply paper cones over a former until the required thickness is built up, the joints in the various constituent cones being staggered and the constituent cones being adhesively secured together. Finally the composite cone is consolidated in a suitable press.

The nosepiece is permanently secured to the tube 11' in any suitable way such as by screws or rivets and an adhesive composition.

A diaphragm disc 11³ is arranged within the nosepiece at the upper end of the conical portion thereof such disc being retained in position by a spacing ring 11⁴ the upper end of which forms an annular seating for a further diaphragm disc 11⁵ which is suitably secured in position. Thus the disc 11³ divides the space below the disc 11⁵ into two sealed air compartments (see Figure 5).

A sealing disc 30 is mounted on the shoulder formed by the upper end of the cylindrical upper portion of the nosepiece and is suitably sealed thereto and the lower end of the tube 15 abuts thereagainst when the container is assembled (see Figures 1 and 5).

A shock-absorbing pad disc 31 which fits neatly within the tube 15 preferably rests on the top of the disc 30 in the nosepiece immediately below the said sealing disc 11⁵, the function of this pad being to absorb shock and thereby assist in preventing damage to the contents when the container strikes the ground or water. As shown in Figure 7 the pad disc may consist of upper and lower chipboard discs having their edges enclosed within a ring of similar material the interior of the disc being filled with sawdust 31¹, sponge or crepe rubber or other suitable material.

A plurality of circumferentially arranged pairs of closely spaced holes 11⁶ corresponding in number to the holes 12⁷ in the parachute bucket are formed in the wall of the percussion nose 11 somewhat above the diaphragm disc 11⁵.

A cord 25 is threaded through these pairs of holes in the manner previously described with reference to the parachute bucket whereby a plurality of projecting loops 25' is formed, though in this case the cords do not extend through any member corresponding to the suspension ring 23 in the parachute bucket.

Finally the coaxially arranged units of the container are secured together by means of an externally arranged tie cord 26 which is threaded

through the projecting loops 24' and 25' in the manner shown in Figure 8—that is to say, the tie cord 26 is passed backwards and forwards along the container and through the loops at the same time progressing around the container. Finally, when the cord is pulled tight, the free ends are tied together as indicated at 26'.

Thus, when the container is launched from an aircraft as previously described and the parachute opens, the container is supported by the suspension ring 23 and the cords 24, 26 and 25 so that the units of the container are securely held together and the weight thereof is evenly distributed.

In order to reduce the length of the tie cord 26 and the time of lacing, the said cord may be passed through adjacent pairs of loops 24' and 25' as indicated in broken lines in Figure 8, the loops 24' and 25' being then preferably longer as shown to reduce the lateral component of the pressure exerted thereby on the parachute bucket.

An alternative method of lacing the cords 24 is indicated in Figure 15 in which the parachute bucket is provided with a circumferential series of evenly spaced holes and the cord 24 passes twice through each hole to form the external loops 24'. Each external loop is preferably fitted with a cardboard tube 27 or the like to prevent its being pulled back into the bucket. It will be obvious that the method is equally applicable to the cord 25 in the percussion nose.

According to another alternative shown in Figure 16 as applied to the percussion nose, an even number of holes is provided and the cord 25 is replaced by a series of grummets 28 consisting of endless cords. The doubled ends of each grummet are passed through a diametrically opposed pair of holes to form external loops through which the tie cord 26 is threaded in the manner already described.

It will be evident however that the container units may be detachably connected together by any other suitable means in lieu of a tie cord as 26. For example, we may employ a circumferentially arranged series of longitudinally extending straps each fitted with a quick release buckle.

When it is desired to carry the container in the bomb rack of an aircraft, it is preferably fitted with one or more encircling metal bands 32 (see Figures 1, 8, 12 and 13). The ends of this band are connected by a pivoted toggle link 32' which, when turned downwardly against the adjacent portion of the band, contracts the latter tightly about the body of the container, the link being then retained in position by a slidable keeper member 32². This keeper is provided with lugs 32⁴ which, when pressed down around the end of the link 32', prevent displacement of the said keeper. A loop 32³ secured to the band enables it to be attached to the bomb rack.

In use the container is loaded with the required materials before the sealing disc 19 and parachute bucket are placed in position, and, when the contents are suitable, one or more additional pad discs as 31 or plain discs of the same size may be inserted at suitable intervals to divide the interior into separate compartments and to assist in absorbing the shock of impact. It will be evident that, even when plain discs are used for this purpose, a certain degree of shock absorbing action is obtained as the discs serve as pistons at the time of impact and compress the air therebelow.

The external joints between the various elements of the container are also rendered water-

tight in any appropriate way and thus the contents are completely sealed and, if not greatly overloaded, the container will float in water.

In use the container is launched from the aircraft in any convenient manner and, when the aforesaid static line becomes taut, the parachute is withdrawn from the parachute bucket, the breaking link in the static line being broken at or about this time.

The shock produced by the opening of the parachute is partly absorbed by the stretching of the shroud lines thereof and of the container tie cords 24, 25 and 26, while additionally the paper container elements possess a useful measure of resilience and yield when subjected to intense pressure by the cords 24 and 25.

Thus the container supported by the tie cords thereof descends with the percussion nose lowermost—i. e. in the attitude shown in Figure 1.

When the nosepiece strikes the ground, it is initially deformed by the force of the impact (see broken lines in Figure 1) at the same time compressing the air in the closed compartments thereof. Axial deformation may be ensured by providing a weakened circumferential zone therein, though this has not been found necessary.

Finally the nosepiece bursts and, during deformation and subsequent bursting, a substantial amount of energy is dissipated by compression and release of the air therein whereby the speed of descent of the container is materially reduced. At this stage the contents of the container tend to move in advance of the container itself thus stretching the lacing cords and slightly elongating the holes through which they pass. In this way a further absorption of energy is effected, and it may here be mentioned that the transverse lacing of the tie cord 25 in the percussion nose provides additional support for the reason that the various traverses do not cross at a point but cover a substantial area. Additional energy is dissipated owing to the resilience of the materials forming the container and the contents are generally found to be in a condition much superior to that experienced with present types of containers known to us.

In order to secure optimum results when the container is dropped on a relatively hard surface, it is important that the percussion nose should burst on impact and, in order to secure this result, it is necessary that the strength of the nose should bear an appropriate relation to the kinetic energy of the container at the time of impact. The required variation in strength of the percussion nose may be obtained when same is formed of multi-ply paper by variation of the number of plies employed and similar considerations apply when same are otherwise formed.

In some cases therefore it may be necessary to replace a percussion nose on a container with one having a different bursting strength, though this would not ordinarily be necessary as in general the total weight of the container and the diameter of the parachute would not be substantially varied in which case the energy requiring absorption at impact would remain substantially constant.

From the preceding description it will be understood that, in order to produce the desired dissipation of energy, the air in the sealed compartment of the percussion nose should be compressed before rupture occurs. That is to say, the percussion nose should deform by crumpling to compress the air until the pressure is sufficient to burst the nose.

Accordingly it may be advantageous under some conditions to modify the construction of the percussion nose so as to facilitate crumpling. Thus for example Figure 17 shows diagrammatically a percussion nose formed of 6 plies of paper each ply being indicated by a single full line. The plies are adhesively secured together as indicated by cross hatching, but in the intermediate zone of the nose, the adhesive is omitted (as shown at 118) between alternate plies in order to reduce the rigidity in this zone. The opposite sides of this figure show alternative arrangements.

In the modification shown in Figure 18, the intermediate zone of the percussion nose is of stepped formation to facilitate crumpling.

It is to be noted also that it is not essential to provide the percussion nose with an air compartment which is sealed as above described, provided the construction of the percussion member is such as to permit of compression of air therein and ultimate bursting of the nose. Thus, for example, if the percussion nose were provided at its lower end with a small axial opening, such opening would be sealed by the crumpling of the material at impact and thereafter compression of the enclosed air would occur. Even one or more small openings near the upper end of the air compartment would not prevent a considerable increase in air pressure during the rapid crumpling of the nose.

Alternatively the air compression compartment may contain sponge rubber or other resilient cellular material providing a multiplicity of air or gas filled cells which may be compressed at impact or the compartment may contain a sealed air filled rubber bag. It will be evident therefore that the air compression compartment does not necessarily constitute a sealed air compartment though this latter construction is preferred.

The construction of the container permits of its being assembled in a relatively compact condition for transport. Thus, as shown in Figure 14, the percussion nose and parachute bucket are reversed whereby these parts project into the hollow body of the container, the various units being retained together by the usual tie cord 26. In this condition, however, it is desirable to protect the then outer ends of the percussion nose and parachute bucket against accidental damage which would militate against the subsequent formation of watertight joints between same and the corresponding ends of the body. For this purpose a composite protector ring 33 is preferably fitted temporarily to the exposed end of the parachute bucket may be protected by causing the inner ring 12⁴ to extend somewhat beyond the end of the main tube 12' as shown in Figures 6 and 14.

It is further to be noted that the larger tubes forming the body of the container are capable of being used as independent containers—e. g. as containers for despatching supplies to forward areas for which purpose they may be fitted with suitable end covers. Likewise these elements and the cords incorporated in the container would often be useful to troops in isolated positions.

In this connection it may in some cases be advantageous (see full lines at the lower right-hand portion of Figure 8), to pass a cord 34 circumferentially around the container and through each of the loops 24' on the parachute bucket, the ends of the cord 34 being then tied together. The tie cord 26 is passed over the cord 34 and around (but not through) each loop 24' as illustrated, a similar arrangement being provided, if desired, at the

percussion nose. The cord 34 may then be cut to release the tie cord 26 whereby the container may be quickly opened as by paratroops without cutting the tie cord 26.

Figure 11 shows a parachute bucket provided with an alternative type of removable cover 35 such cover being formed of semi-rigid material such as cardboard. The static line 21 passes outwardly through the center of the cover and then over the surface thereof to the upper end 5 of the parachute bucket 12 which it encircles once as shown at 21', this turn being covered by a strip 36 of paper or other rupturable material which normally retains the cover to the bucket.

10 The static line is then wound several times around a grooved intermediate portion of the cover as shown at 21², such turns being normally retained in position by the rupturable cover strip from which the free end of the static line projects.

When the container is released from the aircraft, the static line is first unwound at 21² at the same time rupturing the relevant part of the cover strip 36. The turn at 21' is then unwound, thus breaking the strip 36 and releasing the cover from the bucket. The cover is then pulled from the bucket and, if it is suitably attached to the static line and parachute, it will act as a pilot parachute for the main parachute.

Among other advantages this type of cover for the parachute has better aerodynamic qualities and is therefore more suitable when the container are to be carried in bomb racks.

From the preceding description it will be evident that the improved container is simply constructed from readily available materials, that it is easy to assemble, and convenient to fill. Furthermore the contents may be quickly removed after the container has landed, while additionally various unitary parts are capable of other uses both before and after the container is dropped.

The shock absorbing qualities of the container permit of a higher terminal velocity which in turn enables a relatively small and inexpensive parachute to be used. This is important because of the resultant saving both in materials and labor.

As already indicated, actual tests have shown that the contents are generally recovered in better condition than is usually the case when other known types of containers are used, while finally the container will float if dropped in water so that in many cases it could be recovered with the contents undamaged and may even serve as a float for life saving purposes in cases of emergency.

The invention is not limited to the use of a percussion nose of conical form, though this shape is preferred. For example, if it is intended to transport the containers on end in an aircraft, they may be provided with flat ended cylindrical percussion noses.

Again a percussion nose of hemispherical form may be used and would probably operate more satisfactorily in the event of its striking the ground when the longitudinal axis of the container was disposed at a substantial angle to the vertical.

Likewise the percussion nose may be of pyramidal form and would be advantageous if, for example, the body of the container were of square shape in cross section. In this case the body members may be formed so as to permit of their being "knocked down" for transport in

the flat and the percussion nose and parachute bucket would serve, in conjunction with suitable intermediate stiffening means, to retain the shape when the container is assembled.

It will also be evident that a body of rectangular cross-sectional shape would in many cases permit of more effective use being made of the storage space.

Containers as described herein may be modified to accommodate anti-personnel, incendiary, time or other type bombs. Thus the use of the container is not restricted to the dropping of supplies.

We claim:

15 1. A container having a storage compartment and comprising a plurality of coaxially arranged interfitting tubular units one of said units being a percussion member located at one end of the container a circumferential series of loops of flexible material projecting externally from spaced units of the container, and longitudinally extending flexible tie means arranged externally of the container and connected to said spaced series of projecting loops whereby the said units 20 are detachably secured together.

2. A container according to claim 1 wherein said flexible material forming the projecting loops extends substantially diametrically across the interior of the respective unit.

30 3. A container according to claim 1 wherein said flexible tie means extends backwards and forwards externally of the container and is passed alternately through projecting loops on at least one of the said spaced units and is also 35 connected to the projecting loops of the other series thereof.

4. A container according to claim 1 wherein the end unit opposite to the percussion member comprises a parachute compartment, a folded 40 parachute therein and shroud lines on the parachute, the said shroud lines being connected to the flexible material forming the projecting loops on the corresponding end unit.

5. A container comprising a plurality of coaxially arranged interfitting tubular units, the unit located at one end being a percussion member and the unit at the opposite end of the container forming a compartment for a folded 45 parachute, a circumferential series of projecting loops of flexible material extending outwardly from each of said end units, longitudinally extending flexible tie means arranged externally of the container and connected to said projecting loops whereby the various units of the container are

50 normally retained together, a folded parachute in said parachute compartment, shroud lines on the parachute, a suspension ring arranged within the parachute compartment and secured to the shroud lines, said suspension ring being additionally connected to the flexible material forming the aforesaid loops on the unit forming the 55 parachute compartment, said percussion member being formed of material having a low tensile strength, low elongation and a relatively high compression strength.

6. A container according to claim 1 wherein said percussion member is of composite construction and comprises a parallel tubular portion secured to and enclosing the upper end of a 60 downwardly converging portion and a transverse partition extending across an upper part of the downwardly converging portion and forming a sealed air compartment therebelow.

70 7. A container comprising tubular means forming a storage compartment and hollow means of

75

semi-rigid rupturable material located between said storage compartment and one end of the container and forming a sealed air compartment, said tubular means comprising at least one outer tubular member and at least one inner tubular member slidably mounted within said outer member and being a neat fit therein, the inner tubular member being so disposed relatively to the outer tubular member that a spigot is formed at one end of the storage compartment and a socket is formed at the other end thereof.

8. A container according to claim 1, wherein the end unit remote from the percussion member contains a compartment for a packed parachute, said compartment being open at its outer end.

9. A percussion head for the purpose described, comprising a hollow compression member having an air-compression chamber, said hollow member being constructed of a cellulosic material whereby it has a low tensile strength, low elongation and a relatively high compressive strength, the compression member including an impact terminal adapted to impact stress so that it will first crumple and thus increase the pressure of the air in such compression member to a point to thereafter rupture such member.

10. A percussion head for the purpose described, comprising a hollow compression member having an air-compression chamber said hollow member being constructed principally of paper pulp, whereby it has a low tensile strength, low elongation and a relatively high compressive strength, the compression member including an impact terminal adapted to impact stress so that it will first crumple and thus increase the pressure of the air in such compression member to a point to thereafter rupture such member.

11. A percussion head for the purpose described, including a hollow member, an air compression compartment therein, said hollow member being constructed principally of cardboard, whereby it has a low tensile strength, low elongation, and relatively high compressive strength, to insure that when the hollow member is subjected to landing impact stresses due to normal con-

ditions of descent pressure under a predetermined value, such hollow member will first crumple to compress the air of such air compartment and thereafter rupture under such air compression.

5 12. A percussion head for the purpose described, comprising a hollow compression head having an air compression chamber, said head being constructed principally of chipboard, whereby it has a low tensile strength, which head 10 when subject to landing impact stresses due to normal conditions of descent pressure above a predetermined value will be caused first to crumple and thereafter to rupture.

15 13. A percussion head for the purpose described, comprising a hollow compression head having an air compression chamber, said head being constructed principally of bonded paper, whereby it has a low tensile strength, which head, when subject to landing impact stresses due to normal conditions of descent pressure above a predetermined value will be caused first to crumple and thereafter to rupture.
